UNITED STATES PATENT OFFICE.

EDWARD J. FELLMAN, OF MILWAUKEE, WISCONSIN.

FASTENER FOR OUTER SASHES AND THE LIKE.

1,189,245.

Specification of Letters Patent.

Patented July 4, 1916.

Application filed January 13, 1916. Serial No. 71,837.

To all whom it may concern:

Be it known that I, EDWARD J. FELLMAN, a citizen of the United States, and resident of Milwaukee, in the county of Milwaukee, and State of Wisconsin, have invented certain new and useful Improvements in Fasteners for Outer Sashes and the like; and I do hereby declare that the following is a full, clear, and exact description thereof.

10 The present invention relates to new and useful improvements in means for holding storm or screen sashes or other pivotally mounted members at a desired inclination to the window frame or other support, and is particularly directed to the provision of a sash holding device of the type embodied in Patent No. 532,483, issued Jan. 15, 1895.

It is primarily the object of the present invention to provide a holding device of this nature which possesses a maximum simplicity of structure consistent with strength and efficiency and a desired convenience of operation. In this latter connection it is an object of the invention to provide in a device of the character set forth and including a sash carried link member and a frame carried keeper member, means whereby the link is normally retained in the keeper member and coacts therewith to provide for an automatic securing of the sash in an inclined position upon swinging it outwardly and wherein the connection of the link and keeper may be instantly released upon a certain manipulation of the link, to permit entire detachment of the sash from the frame.

A sash holding device of the present nature generally comprises in addition to the link and keeper members, a catch carried by the sash and adapted to receive the link member upon its being passed through the keeper and folded along the sash to thus hold the sash tightly against the frame, and it is a further object of the present invention to provide a structure whereby, when the sash is detached from the frame, the link member may engage and be held in the catch and may be released therefrom only upon a twisting flexure of the link whereby detachment of the link from the catch due to jarring or other accidental causes is prevented so that the link is at all times held against hanging loose from the sash when the sash is detached and transported.

It is still further an object to provide a device of the present nature wherein the

parts are mutually interchangeable for both sides of a window structure to thus obviate the necessity of providing right and left hand parts.

With the above and other objects and advantages in view, the invention resides more particularly in the novel combination, arrangement and formation of parts more particularly hereinafter described and particularly pointed out in the appended claims.

In the drawings: Figure 1 is a vertical sectional view taken through the lower portion of a window having a pivotally suspended screen sash holding device associated therewith and in a position holding the sash extended. Fig. 2 is a view similar to Fig. 1, but showing the sash closed, with the improved device locking it in a closed position. Fig. 3 is a transverse sectional view on the line 3—3 of Fig. 1. Fig. 4 is a transverse sectional view through the catch member on the line 4—4 of Fig. 2. Fig. 5 is a vertical sectional view on the line 5—5 of Fig. 1, and showing the relation of parts assumed to detach the link from the keeper member. Fig. 6 is a perspective view of the keeper member.

Referring now more particularly to the accompanying drawings, 5 designates a window frame, and 6 designates a screen sash member.

The improved holding device comprises a link member 7, which is pivotally secured to a side of the sash 6 by a bracket member 8 including a plate having laterally turned ears 9 at its sides receiving one end of the link therebetween. The other end of the link is provided with a head 10, which is formed by bending the end of the link in the shape of an eye, and the bottom edge of the link immediately rearwardly of the head is provided with a locking notch 11.

The keeper member comprises an angular plate 12 which has one side bolted to a respective side of the window frame 5 and its other side projected laterally and provided with a vertical slot 13 through which the link 7 is passed. This slot is of a width slightly less than the width of the head 10 and thus normally the head is prevented from withdrawal from the keeper, but to provide for such withdrawal when it is desired to remove the sash, the intermediate portion of the slot 13 is provided with a lateral extension 14 which extends into that

side of the keeper which is bolted to the frame, and thus the slot at that point has a width equal to its normal width plus the thickness of the material of the keeper which provides sufficient width to permit passage of the link head 10.

The foregoing structure procures a proper intermediate widening of the slot 13 with a minimum weakening of the plate due to lack of material at such widened portion, and although this structure is preferable, any structure which procures an intermediate widening of the slot may be utilized as for instance, the slot may be widened into the projecting side of the keeper member, or both sides of the slot may be widened, these slight modifications of structure being obvious. In normal operation, however, the weight of the link holds it in the lower portion of the slot 13 and thus provides against withdrawal, and the sash is secured in an open position by merely swinging it outwardly, the notch 11 during such swinging movement receiving the lower edge of the slot 13 whereby the link is held. To permit closing of the sash it is merely necessary to trip the link upwardly.

The catch member of the device comprises an angular plate 15 which has one side secured to the side of the sash as by the headed screw 16, the plate being held against rotation on the screw by inwardly struck spurs 17, engaging in the sash. The other side of the plate has its free end directed inwardly of the sash to form a holding portion and to define a link receiving recess in conjunction with the rest of the plate and the free end of this holding portion carries a retaining lip 17. When the sash is closed, the link 7 is disposed with its pivotal connection inwardly of the projecting side of the keeper and may thus swing to be engaged in the catch member, the catch member being disposed on the sash below the link, although it is noted that it could be disposed above the link if desired. To engage the link in the catch member it is necessary to procure a slight twisting flexure of the link, which is of somewhat resilient material, and this necessary twisting flexure to procure detachment of the link from the catch prevents accidental detachment.

When the sash is detached from the window, the link is engaged in the catch and is thus held against swinging loose when the sash is transported. It is noted that the head of the securing screw 16 of the plate is disposed in such relation to the lip 18, as more particularly indicated in Fig. 4, that a possible jarring to cause a springing detachment of the link from the catch is prevented by abutment of the link with this screw head, and to detach the link it is necessary to impart thereto a positive twisting flexure, as indicated by the arrow in Fig. 4,

it being thus noted that the screw 16 and lip 18 form a reduced throat portion of the link receiving recess.

An exceedingly simple and efficient device is thus provided which may be formed entirely of sheet metal, and which has its parts adapted for application to either side of a window structure whereby the necessity for the provision of right and left hand parts is obviated.

Although the necessary resiliency to procure a proper coöperation between the link and catch member has been described as contained in the link, it is obvious that this resiliency could be as well contained in the lugs 9 of the attaching bracket of the link and in this latter instance the link could be made of thicker material. It would be also possible for the resiliency to be disposed partly in the lugs and partly in the link strip to procure sufficient resilient flexure.

A common disadvantage encountered in various types of sash fasteners is that a rattling of parts is permitted due to action of the wind on the sash, and it is noted that in the present structure there are no loose connections to procure such rattling, as the edge of the keeper member fits snugly in the notch 11 of the link and the link is firmly secured to the sash by the bracket member. Under extreme weather conditions it might, however, be possible for the wind to exert a jerking action on the sash which would tend to swing the link upwardly on its pivot, and it is observed that provision is made against accidental withdrawal of the link from the keeper in such movements of the link by the fact that the extension 14 of the keeper slot is of a width substantially equal to the transverse width of the link head 10 whereby a relative nicety of manipulation is necessary in positioning the head member to withdraw it from the keeper, and whereby if the link were accidentally thrown upwardly it would move past the extension 14 and be held in the upper portion of the keeper slot 13 and would in subsequent movement drop to the bottom of the slot.

I claim:

1. A swinging sash holder comprising a link member provided with a notch in one edge, means for pivotally connecting one end of said member to a sash, a keeper member provided with a slot reduced in its lower portion, and a head on the other end of the link member movable through the slot and of greater width than the said reduced portion of the slot.

2. A swinging sash holder comprising a link member provided with a notch in one edge, means for pivotally connecting one end of said member to a sash, a keeper member comprising an angular plate having one side adapted for securing to a support and provided in its other side with a longi-

tudinal slot having an extension into said first named side, and a head on the other end of the link member movable through the slot at its extension.

5 3. In a swinging sash holder the combination of a resilient link strip adapted for pivotal connection with a sash and a catch member having a recess adapted for connection with a sash and adapted to receive the link 10 strip and including a reduced throat portion of lesser width than the width of the link strip necessitating a twisting flexure of the strip to pass therethrough.

4. In a swinging sash holder, the combination of a resilient link strip adapted for pivotal connection with a sash, and a catch member adapted also for connection with a sash and comprising an angular plate, a headed securing member passed through one 20 side of the plate, the free end of the other side being bent inwardly to form a holding portion, an inturned lip on the holding portion and the relation of the lip and securing

member being such as to necessitate twisting flexure of the link strip to pass therebetween. 25

5. A swinging sash holder, comprising a link member provided with a notch in one edge, means for pivotally connecting one end of said member to a sash, a keeper member adapted for connection with a support 30 and provided with a slot, an intermediate portion of the slot being enlarged and a head on the other end of the link member of substantially the same cross-sectional area as the enlarged portion of the slot whereby 35 retraction of the head through the slot except upon an approximately exact intermediate positioning of the head is prevented.

In testimony that I claim the foregoing I 40 have hereunto set my hand at Milwaukee, in the county of Milwaukee and State of Wisconsin, in the presence of a witness.

EDWARD J. FELLMAN.
